FOREIGN PATENT DOCUMENTS

EP 0802827 B1 8/1998

Primary Examiner—Paula A. Greene

(74) Attorney, Agent, or Firm—McCarter & English LLP

CLAIM

The ornamental design for a pump for a dispenser, as shown and described.

DESCRIPTION

FIG. 1 is a front perspective view of a pump showing our new design;

FIG. 2 is a front elevational view of the pump of FIG. 1; FIG. 3 is a side elevational view of the pump of FIG. 1; FIG. 4 is a rear elevational view of the pump of FIG. 1; FIG. 5 is a second side elevational view of the pump of FIG. 1;

FIG. 6 is a top plan view of the pump of FIG. 1; and, FIG. 7 is a bottom plan view of the pump of FIG. 1.

The broken lines shown in the drawing figures are for illustrative purposes only and form no part of the claimed design.
